UNITED STATES PATENT OFFICE.

AUGUST SWANSON, OF RED WING, MINNESOTA.

ALBUM.

SPECIFICATION forming part of Letters Patent No. 727,022, dated May 5, 1903.

Application filed March 24, 1902. Serial No. 99,606. (No model.)

To all whom it may concern:

Be it known that I, AUGUST SWANSON, a citizen of the United States, residing at Red Wing, in the county of Goodhue and State 5 of Minnesota, have invented certain new and useful Improvements in Albums; and I do declare the following to be a full, clear, and exact description of the invention, such as will enable others skilled in the art to which 10 it appertains to make and use the same, reference being had to the accompanying drawings, and to the figures of reference marked thereon, which form a part of this specification.

15 My invention relates to improvements in albums, and has for its purpose the providing of an inexpensive and durable album in contradistinction to the ordinary albums the leaves of which are easily torn by the insertion and exchange of pictures in same. This and other objects I attain by the novel construction and arrangement of parts illustrated in the accompanying drawings, in which—

Figure 1 is a perspective view of my complete album closed. Fig. 2 is an end view of the album opened and with pictures in dotted lines. Fig. 3 is a top view of the album opened and with the cover and some of the picture-holding clasps removed. Figs. 4 and 5 are modifications of the picture-holding clasps. Fig. 6 is an end view of one of the clasps with two pictures held in it. Fig. 7 is a further modification of the picture-holding clasp. Fig. 8 is an end view of Fig. 7. Fig. 9 is an end view of the album, showing a modification in the arrangement of its cover; and Fig. 10 is a front view of a portion of Fig. 3, showing more clearly the brace 4 and its slot sliding on the peg 5.

40 Referring to the drawings by reference-numerals, the case of the album consists of the bottom 1, and the end pieces 2, hinged at 3 to the bottom, so as to fold outward to a level position with the bottom, in which position 45 they are held by the braces 4, (shown in Fig. 3,) which are slidable in their upper point of fastening 5, which secures them to the only rigid side 6 of the album. To the top of the side 6 is hinged at 7 the cover 8, to which the 50 side 9 of the case is secured. This is my preferred style of the case, while I may also put

the hinges 7 at the point 7^a in Fig. 9 and let the parts 8 and 9 turn open, as shown in dotted line. When the case is closed, the pegs 10 enter the cavities 11 in the upper edge of the 55 end pieces 2 and hold them locked, while the hook 12 engages a staple 13 in Fig. 1 or a peg 13^a in Fig. 3 and holds the side cover 8 closed and the side 9 down upon its supporting pegs 14.

60 As a substitute for leaves in the album I provide a series of wire clasps 15, which are hinged to the bottom of the case by staples 16, preferably in the manner shown in Figs. 4 and 5. The clasp may also be made of sheet 65 metal, like 15^a in Figs. 7 and 8, and secured by a long staple or wire 16^a. In either form the clasp is made flexible enough to receive and hold between its upper parts either a single portrait or picture 17 or two of them 70 turned back to back, as in Fig. 6, and it is evident that the pictures may be put with either bottom end or one of the longer edges in the clasps, as indicated in dotted lines in Fig. 2, where is also indicated that small pictures may be placed one in each half of the clasp.

75 In order to house the greatest possible number of pictures in the album, I provide upon each end wall of the case clasps 18, under 80 which pictures may be held, like 19 in Fig. 3.

It will be readily understood that the spring-wire clasp 5, being made of spring-wire, holds by spring force the cards or pictures between the crossing bars 20 and 21 in Fig. 5, while 85 the bows 22 23 also help to hold and support the pictures. It will further be understood that in the use of the album the pictures, with their clasps, are turned from side to side like leaves of a book and when released from 90 the hand will rest in a slanting pile toward one or both end walls 2, which support the first part of the pile, as shown to the right in Fig. 3 and indicated by the two empty clasps leaning toward the left. It will also be understood that the wire clasps and staples are placed zigzag on the bottom of the case, which 95 gives the clasps a chance to fold more horizontally than if the crossings of the wire in one clasp were allowed to meet the crossed wires of the next clasp. Finally it will be understood that the pictures are prevented 100

from chafing by the engagement or touching of the wire clasps against each other between the pictures.

Having thus described my invention, what I claim, and desire to secure by Letters Patent, is—

An album comprising a case and picture-holding spring-clasps pivoted or hinged upon its bottom; said case having its ends hinged to the bottom and adapted to fold outward to form supports for the pictures and the braces

4 supporting said end pieces in a horizontal position; the cover and one side of the case being hinged so as to open the case and exhibit the pictures properly, substantially as shown and described.

In testimony whereof I affix my signature in presence of two witnesses.

AUGUST SWANSON.
